(57) **CLAIM**

The ornamental design for a cap, as shown and described.

DESCRIPTION

FIG. 1 is a top perspective view of a cap having the cap in accordance with our design;

FIG. 2 is a top end view of a cap having the cap in accordance with our design;

FIG. 3 is a first side elevational view of a cap having the cap in accordance with our design, the opposite side of the cap being the same;

FIG. 4 is a bottom end view of a cap having the cap in accordance with our design; and,

FIG. 5 is a front elevational view of a cap having the cap in accordance with our design, the opposite side the cap being the same.

Those portions of the drawings depicted in evenly spaced broken lines show portions of the cap that form no part of the claimed design, with the dash-dot-dot lines being representative of the boundaries of the claimed areas of the designs.

1 Claim, 3 Drawing Sheets

FIG. 1

FIG. 2**FIG. 3**

FIG. 4

FIG. 5
